UNITED STATES PATENT OFFICE.

PETER FLETCHER, OF MIDLAND, CANADA.

WAGON-GEAR.

SPECIFICATION forming part of Letters Patent No. 770,746, dated September 27, 1904.

Application filed December 18, 1903. Serial No. 185,758. (No model.)

To all whom it may concern:

Be it known that I, PETER FLETCHER, blacksmith, a subject of the King of Great Britain, residing in the town of Midland, in the county 5 of Simcoe, in the Province of Ontario, Canada, have invented certain new and useful Improvements in Wagon-Gears, of which the following is a specification.

My invention relates to improvements in 10 wagon-gears; and the objects of my invention are, first, to construct a comparatively light yet very strong wagon-gear out of iron and steel; secondly, to provide a wagon-gear with an adjustable reach, and, thirdly, to make the 15 line of draft as near on a line as possible with the center of the wheels, and thus prevent undue straining of the wagon-gear; and it consists in constructing the benches of either I-beam or T-beam steel and connecting them 20 together by a reach preferably tubular in construction and providing said benches with stub-axles to mount the wheels on.

My invention further consists in a particular construction of tongue and braces or supports for same.

The construction of my gear will be herein-after fully explained.

Figure 1 is a plan view of my gear, showing same partly in section. Fig. 2 is a side elevation of my gear, showing a vertical cross-section on the line *a b*, Fig. 1. Fig. 3 is a view of the under side of one of the benches, showing the stub-axles secured thereto; and Fig. 4 is a view of the under side of an alternative 35 form of bench, partly in section, showing the stub-axles secured thereto.

In the drawings like letters of reference indicate corresponding parts in each figure.

Although I show and describe a particular 40 construction for securing the tongue to my wagon-gear, it must be understood that I do not confine myself to same.

In my preferred form of invention the benches *A* are made of I-beam steel and are 45 connected together by a suitable reach. The preferred form of reach used by me is made tubular and consists of the back member *B*, secured to the back bench *A'*, which slides within the front member *C*, pivoted to the 50 front bench *A*. Bracing the back member

B of the reach to the bench *A'* are channel-irons *D*. The form of coupling *I* use for securing the reach to the bench *A'* is constructed as follows; but I wish it understood that I do not confine myself to any particular manner 55 or construction for coupling the reach to the front bench.

E is a piece of channel-iron secured at its rear end to the member *C* and having its front end *e* resting upon the top of the bench *A'*. *E* is another piece of channel-iron secured to the member *C* and having its front end resting upon the flange *a* of the bench *A'*.

Resting upon the top of the bench *A'* is a bolster *F*, constructed of I-beam steel. The 65 bolster *F* is provided with any suitable standards *f*. In order to prevent the weight of the bolster *F* and weight carried thereby interfering with the movement of the end *e* of the member *E* of the reach-coupling, I suitably secure to the top of the bench *A'* a metal 70 plate *b*, which spans the end *e* and is secured to the top of said bench by its ends *e'*, which are the only parts of said plate which rest upon said bench. The reach-bolt *G* passes 75 down through the plate *b*, end *e*, and flanges *g* and *a* of the bench *A'*, thus securing the reach to said bench. By means of the plate *b* just described it will be understood that the reach-coupling and bench *A'* will have 80 free movement independent of each other. In the drawings I have shown the king-bolt *H* held in the front flanges of the bolster *F* in the plate *b* and the flanges *h* and *i* of the bench *A'*. I of course do not restrict myself 85 to any particular way of mounting the king-bolt in place.

I preferably construct the reach-coupling of two members *B* and *C* before described, so that I may be able to lengthen or shorten the 90 distance separating the benches. Although I have shown the said coupling and described same as being tubular, I do not confine myself to this particular shape. Passing down through the front member *C* and through the 95 back member *B* by means of the holes *j* and the elongated slots formed respectively therein is the reach-coupling bolt *I*. The holes or slots *c*, formed in the back member *B*, are constructed with their greatest length at right 100

angles to the length of said member, so as to allow the members of the reach-coupling to have a certain amount of axial movement, thus relieving undue straining on the wagon-gear. In case I wish to increase the distance separating the benches I remove the reach-coupling bolt I and pull the members of the reach-coupling apart the required distance and then couple same together by means of 5 said reach-coupling bolt I and the slots or holes before described. It will be understood that the reach-coupling bolt I has snug fit within the holes *j* formed in the front member C and the sides of the elongated slots or 10 holes *c* in order to prevent longitudinal movement of the members of the reach-coupling. The tongue J is preferably constructed tubular and is provided with two braces K, constructed of channel-iron suitably secured 15 thereto. The rear end of said tongue is suitably braced to said braces K by means of the braces *l*.

L represents channel-irons suitably secured to the bench A² and overlap for a certain distance the rear ends of the braces K. These channel-irons are braced by channel-irons *l*' to the bench A². Having bearing in the channel-pieces L, braces K, and passing through the rear portion of the tongue is the bolt M, 30 which couples said tongue to said channel-pieces L.

I mount the wheels N on the benches by means of stub-axles O, which may be secured to or formed a part of said benches. I preferably attach the said stub-axles to the benches by the following preferred construction: The inner ends of said stub-axles are flattened out, as shown at *o*, and riveted to the under side O' of said benches. The portion O² of said 35 stub-axles is formed square and is embraced by the metal strap O³, the ends of which extend through the lower flanges O⁴ of the rear bench A' and through the flanges *a* and *i* of the front bench A² and are threaded and provided with nuts O⁵, which hold same securely 40 in place. To additionally secure the stub-axles in alinement on said benches, I suitably secure to the under side O' of said benches angle-pieces O⁶, which abut against the square 45 sides of the portion O² of said stub-axles.

I have described my preferred form of bench; but it must be understood that I do not confine myself to using I-beam steel. Upon referring to Fig. 4 it will be seen that 50 I have shown an alternative form of bench. This bench 2 is constructed of T-beam steel. Secured to or forming part of the web 3 of same I provide suitable angle pieces or blocks 4 on each side of said web, to which the said 55 stub-axles may be secured. 5 is an angle piece or block suitably secured to or forming part of the web 3 to provide a lower bearing 60 for the reach-bolt G, and 6 is an angle piece or block also secured to said web to provide 65 a lower bearing for the king-bolt H.

It will be noticed that I have countersunk the head of the reach-bolt G in the plate *b*, so as to prevent same interfering with the movement of the bolster F.

It will of course be understood that I may 70 make changes in the construction of my wagon-gear without departing from the spirit of my invention.

What I claim as my invention is—

1. A wagon-gear comprising front and rear 75 I-beam-steel benches; stub-axles of same; a tubular reach-coupling comprising a rear member secured to the rear bench, and a front member pivoted to the front bench, said members fitting one within the other and provided 80 with slots or holes to allow of their axial movement, and a coupling-pin passing through the holes or slots in the members of said reach-coupling to couple same together.

2. A wagon-gear comprising front and rear 85 I-beam-steel benches; stub-axles of same; a tubular reach-coupling comprising a rear member secured to the rear bench, and a front member pivoted to the front bench, said members fitting one within the other and provided 90 with holes or slots to allow of their axial movement; a coupling-pin passing through the holes or slots in the members of said reach-coupling to couple same together, and channel-irons bracing the rear member of said 95 reach-coupling to said rear bench.

3. A wagon-gear comprising front and rear 100 I-beam-steel benches; stub-axles of same; a tubular reach-coupling comprising a rear member secured to the rear bench, and a front member pivoted to the front bench, said members fitting one within the other and provided 105 with holes or slots to allow of their axial movement; a coupling-pin passing through the holes or slots in the members of said reach-coupling to couple same together; channel-irons bracing the rear member of said 110 reach-coupling to said rear bench; a lower channel-iron secured to the front end of said front member of said reach-coupling; an upper 115 channel-iron secured to the front end of said front coupling and resting upon the top of the front bench; a metal plate secured to the top of said front bench and spanning the end of said upper channel-iron, and a reach-bolt 120 pivoting said upper and lower channel-irons to said front bench.

4. A metal bench for wagon-gears constructed of I-beam steel, and provided at its under side with stub-axles, the inner ends of 125 which are flattened out and secured to said bench; metal straps extending around said stub-axles and additionally securing same to said bench, and angle-pieces secured to said bench and abutting the sides of said stub-axles so as to securely hold same in alinement.

5. A bench for wagon-gears constructed of I-beam steel, and provided, on its upper side near its center portion, with a plate held above 130

the top of said bench except at its ends which are bent downward and secured to said bench.

6. A tongue-coupling for wagon-gears comprising a front bench constructed of I-beam steel, two channel-iron braces secured to the web of same and projecting forward; a tongue constructed of tubular metal; two channel-iron braces secured thereto and resting, in part, adjacent said channel-iron braces secured to said bench, and a bolt passing through the rear end of said tongue and pivoting same in said channel-iron braces.

7. A wagon-gear comprising front and rear metal benches, and a tubular reach comprising a rear member secured to said rear bench and a front member pivoted to said front bench, the said members fitting one within the other and being provided with holes or slots to allow of their axial movement, and a reach-coupling pin passing through the said

holes or slots in the members of said reach-coupling and securing same together.

8. A wagon-gear comprising front and rear I-beam-steel benches, and a tubular reach comprising a rear member secured to said rear bench and a front member pivoted to said front bench, the said members fitting one within the other and being provided with holes or slots to allow of their axial movement, and a reach-coupling pin passing through the said holes or slots in the members of said reach-coupling and securing same together.

In testimony whereof I have signed my name to this specification in the presence of two subscribers.

PETER FLETCHER.
